DESIGN FOR AN OPHTHALMIC MOUNTING

Ernest J. Brusell, St. Paul, Minn., assignor to
American Optical Company, Southbridge,
Mass., a voluntary association of Massachusetts

Application September 8, 1941, Serial No. 103,218

Term of patent 14 years

To all whom it may concern:

Be it known that I, Ernest J. Brusell, a citizen of the United States of America, residing at St. Paul, in the county of Ramsey and State of Minnesota, have invented a new, original, and ornamental Design for Ophthalmic Mountings, of which the following is a specification, reference being made to the accompanying drawing forming a part thereof.

Fig. 1 is a front elevational view of an ophthalmic mounting embodying my new design;

Fig. 2 is a top plan view of the mounting shown in Fig. 1 with the temples removed for convenience of illustration.

The characteristic features of the design are shown in full lines in the drawing.

I claim:

The ornamental design for an ophthalmic mounting, substantially as shown and described.

ERNEST J. BRUSELL.
